UNITED STATES PATENT OFFICE.

JAMES T. HAMBAY, OF WILKINSBURG, ASSIGNOR TO THE UNION SWITCH AND SIGNAL COMPANY, OF PITTSBURG, PENNSYLVANIA.

ANTI-FRICTION GUIDE FOR SIGNAL-RODS.

SPECIFICATION forming part of Letters Patent No. 416,783, dated December 10, 1889.

Application filed August 19, 1889. Serial No. 321,271. (No model.)

To all whom it may concern:

Be it known that I, JAMES T. HAMBAY, a citizen of the United States, residing at Wilkinsburg, in the county of Allegheny and State of Pennsylvania, have invented or discovered certain new and useful Improvements in Anti-Friction Guides for Signal-Rods, of which improvement the following is a specification.

- 10 The invention described herein relates to certain improvements in anti-friction guides for pipes or rods connecting switches and signals with their operating mechanism. These guides, as heretofore constructed, consist of a grooved roller provided with trunnions which are supported upon short horizontal bars having upturned ends serving as stops to prevent the rollers from dropping out of position, said bars being secured to or formed
- 15 integral with a common base. In lieu of these bars with upturned ends the trunnions of the rollers have been mounted in horizontal slots formed in posts or standards independent of or separable from each other in order
- 20 to permit of the insertion of the trunnions into the slots. The construction first mentioned is objectionable on account of the liability of the rollers being dismounted from the bars, no provision being made to prevent a tipping
- 25 30 up of the rollers by an irregularity in the alignment of the signal pipes or rods or in their movements. The other construction is objectionable for the reason that the slots are of necessity formed in independent posts for the reason above stated, thus increasing the cost of manufacture and erection of such guides.

The object of the invention described herein is to so construct the guides as will prevent any accidental dislodgment of the rollers and permit of a series of the supporting-posts being secured to or formed integral with a common base-plate.

In general terms the invention consists in the construction and arrangement of parts, all as more fully hereinafter described and claimed.

In the accompanying drawings, forming a part of this specification, Figure 1 is a view in front elevation of my improved guides; and Fig. 2 is a side elevation of the same.

In the practice of my invention, two, three, or more cheek-pieces or side plates 1 are

formed integral with or secured to a common base-plate 2. The cheek-pieces are provided in their upper ends with horizontal slots 3, and through the upper walls of the slots are formed openings 4, through which the trunnions 5 of the grooved guide-rollers 6 are passed when adjusting the latter in position. The walls of the slots are made of a sufficient width relative to the length of the trunnions to afford bearing-surface for the trunnions of two adjacent rollers without said trunnions coming in contact with each other, as shown in Fig. 1. The openings 4 in the several cheek-pieces are in line with each other and are made of a width slightly greater than the diameters of the trunnions, so that the latter will enter freely when at right angles, or approximately so, with the cheek-pieces. It will be readily seen that the trunnions will be held from accidental displacement by the upper walls of the slots, and that by forming the openings 4 through the upper walls of the slots the rollers can be readily placed in and removed from position, while the several cheek-pieces form an integral structure with a common base-plate.

The pipes or rods are held in position on the grooved rollers by rollers 7, mounted on a rod 8, passing through eyes formed in the upper ends of posts 9, projecting up from the cheek-pieces 1, said rollers being especially useful in preventing any upsetting of the guide-rollers 6 by the movement of the signal pipe or rod where the same passes in a curved path around obstructions.

I claim herein as my invention—

The combination of a base-plate, a series of two or more cheek-pieces fixed thereto and provided with horizontal blocks having openings to their upper walls, a guide-roller provided with trunnions mounted in said slots, and retaining-rollers mounted in posts projecting upwardly from the cheek-pieces, said retaining-rollers serving to prevent the accidental displacement of the guide-rollers, substantially as set forth.

In testimony whereof I have hereunto set my hand.

JAMES T. HAMBAY.
